H. O. HEM

PIVOT MOUNTING

Filed Oct. 19, 1921

FIG. I.

FIG. II.

FIG. III.

Inventor
HALVOR O. HEM.

By *John Marshall*
Attorney

UNITED STATES PATENT OFFICE.

HALVOR O. HEM, OF TOLEDO, OHIO, ASSIGNOR TO TOLEDO SCALE COMPANY, OF
TOLEDO, OHIO, A CORPORATION OF NEW JERSEY.

PIVOT MOUNTING.

Application filed October 19, 1921. Serial No. 508,708.

To all whom it may concern:

Be it known that I, HALVOR O. HEM, a citizen of the United States, residing at Toledo, in the county of Lucas and State of Ohio, have invented certain new and useful Improvements in Pivot Mountings, of which the following is a specification.

This invention relates to pivot mountings, and particularly to means for securing knife edge pivots to scale levers.

One of its principal objects is the provision of reliable and inexpensive means for securing pivots to scale levers.

Another object is the provision of a mounting which may be fixed in place upon the scale lever by means of simple tools.

Still another object is the provision of a pivot mounting which may be secured to the lever in any desired position and which requires no preparation of the lever to receive it other than the boring of a cylindrical hole.

Other objects and advantages will be apparent from the following description, in which reference is had to the accompanying drawings illustrating a preferred embodiment of my invention and wherein similar reference numerals designate similar parts throughout the several views.

In the drawings:—

Figure 1 is a fragmentary elevation of a lever having pivots secured thereto by means of my improved device;

Figure 2 is an enlarged sectional view taken substantially on the line 2—2 of Figure 1, the fulcrum stand being omitted; and

Figure 3 is an enlarged perspective view of the pivot mounting disassembled and detached from the lever.

Referring to the drawings in detail, the lever 1 may be of any desired type. My invention is, however, particularly applicable to levers which must be made especially for particular installations. When scales are installed in factories and other industrial establishments it is often desirable to place the commodity-receivers and indicating mechanism in such relative positions that special extension levers are required to connect them. For the scale manufacturer to carry a sufficiently varied supply of extension levers would involve an investment in patterns, tools, drawings and stock which would not be justified by the returns from installations of this type. By the use of my

invention, however, the pivots may be easily located in any desired position on suitable "blank" levers or upon bars which may be easily cut to the desired length from regular commercial stock.

In mounting the pivots, suitable cylindrical apertures 2 are bored in the lever, these apertures being of the proper size to snugly receive the shank portions 3 of the pivot retainer, the body of which, as is clearly shown in Figure 3, is shaped substantially like a cap screw, having a poly-sided head 4 at one end and threads 5 at its other end. Extending axially into each end of the pivot retainer body is a tapered hole 6 and driven tightly into the tapered holes 6 are the similarly tapered shanks 7 of knife edge pivots 8, the edges of which are in exact alignment.

Extending transversely through the body of the pivot retainer is an opening 9 into which the ends of the pivot shanks 7 extend. If it be desired to remove the pivots from the retainer, a drift may be driven into the opening 9 and the shanks 7 thus forced out of the tapered holes 6.

To secure the pivot retainer to the lever it is only necessary to insert the shank 3 in the opening and clamp the device in place by means of the nut 10, care being, of course, taken to see that the knife edge pivots are properly located when the device is finally clamped in place.

While it will be apparent that the illustrated embodiment of my invention herein disclosed is well calculated to adequately fulfill the objects primarily stated, it is to be understood that the invention is susceptible to variation, modification and change within the spirit and scope of the subjoined claims.

Having described my invention, I claim:

1. In a device of the class described, in combination, a pivot retainer having a portion adapted to be passed through a lever, a shoulder at one end of said portion said shoulder adapted to engage one of the sides of the lever, means adapted to engage the other side of said lever for clamping the pivot retainer in position, and a knife edge pivot separably secured to said pivot retainer.
2. In a device of the class described, in combination, a pivot retainer having a por-

tion adapted to be passed through a lever, a shoulder at one end of said portion adapted to engage one side of the lever, means adapted to engage the other side of said lever for clamping the pivot retainer in position, a tapered opening in said pivot retainer, and a knife edge pivot having a shank driven into said tapered opening.

3. A device of the class described, in combination, a pivot retainer having a portion adapted to be passed through a lever, a shoulder at one end of said portion adapted to engage one side of the lever, means adapted to engage the other side of said lever for clamping the pivot retainer in position, tapered openings extending into each end of said pivot retainer, and knife edge pivots having tapered shanks driven into said tapered openings.

4. In a device of the class described, in combination, a pivot retainer having a portion adapted to be passed through a lever, a shoulder at one end of said portion adapted to engage one side of the lever, means adapted to engage the other side of said lever for clamping the pivot retainer in position, a tapered opening in said pivot retainer, and a knife edge pivot having a shank driven into said tapered opening, there being a transverse opening through said pivot re-

tainer intersecting said tapered opening at substantially the end of said shank.

5. In a device of the class described, in combination, a pivot retainer having a portion adapted to be passed through a lever, a shoulder at one end of said portion adapted to engage one side of the lever, means adapted to engage the other side of said lever for clamping the pivot retainer in position, tapered openings extending into each end of said pivot retainer, and knife edge pivots having tapered shanks driven into said tapered openings, there being a transverse opening in said pivot retainer intersecting said tapered openings adjacent the ends of said shanks.

6. In a device of the class described, in combination, a pivot retainer of substantially cap screw shape having tapered openings extending axially into its ends, a centrally located transverse opening intersecting said tapered openings, and knife edge pivots having shanks driven into said tapered openings and extending into said transverse openings.

HALVOR O. HEM.
